(57) **CLAIM**

The ornamental design for a wire installing tool as shown and described.

DESCRIPTION

1. Wire installing tool

1.1 : Perspective

1.2 : Perspective

1.3 : Front

1.4 : Back

1.5 : Left

1.6 : Right

1.7 : Top

1.8 : Bottom

1.9 : Perspective view shown in an assembled position

The broken lines in the reproductions depict portions of the wire installing tool that form no part of the claimed design; the explanatory curved bracket in the reproductions shows the association of elements and forms no part of the claimed design.
